DESIGN FOR A DESIGN APPLICABLE TO GLASSES OR SIMILAR ARTICLES.

45,528.

Specification for Design.

Patented Mar. 31, 1914.

Application filed December 17, 1913. Serial No. 807,352. Term of patent 14 years.

● *To all whom it may concern:*

Be it known that I, ADRIEN GREDELUE, a citizen of France, residing at New York city, in the State of New York, have invented a new, original, and ornamental Design Applicable to Glasses or Similar Articles, of which the following is a specification, reference being had to the accompanying drawing, forming part thereof.

The figure is an elevation of a glass or similar article showing the application of my new design.

The design is shown applied to an ordinary drinking glass, or similar article, the shape of which is not claimed.

I claim:

The ornamental design applicable to a glass or similar article, substantially as shown.

ADRIEN GREDELUE.
